Primary Examiner — Patricia Palasik(74) *Attorney, Agent, or Firm* — Sheppard Mullin Richter & Hampton LLP(57) **CLAIM**

The ornamental design for a multi-sided power disk, as shown and described.

DESCRIPTION

FIG. 1 is a front-side view of the multi-sided power disk; FIG. 2 is a first perspective view of the front side of the multi-sided power disk;

FIG. 3 is a second perspective view of the front side of the multi-sided power disk;

FIG. 4 is a third perspective view of the front side of the multi-sided power disk;

FIG. 5 is a first side view of the multi-sided power disk;

FIG. 6 is a second side view of the multi-sided power disk; and,

FIG. 7 is a third side view of the multi-sided power disk. The subject matter in broken lines forms no part of the claim.

1 Claim, 7 Drawing Sheets(56)
